CONTAINER

Russell C. Taylor, Greenwich, Conn., assignor to
 American Can Company, New York, N. Y., a
 corporation of New Jersey

Application May 28, 1941, Serial No. 395,663

1 Claim. (Cl. 229—5.6)

This invention relates to fibre containers for the packaging and delivery of liquids such as milk and the like and has particular reference to the construction of an end seam which strengthens a container and which produces a leak-proof bottom end joint. In certain respects, the present invention constitutes an improvement upon the container illustrated and described in the John M. Hothersall Patent 2,085,979, issued July 6, 1937, and is especially an improvement on the angular neck-in bottom end joint of the Hothersall container.

In the production of rectangular fibre containers of the Hothersall type, it has been the practice as a part of such procedure to form a rigid supporting truss portion at the open ends of a tubular container body to brace the body walls against inward and outward movement. Such a truss portion also forms a part of the base of the end seam joint, the body wall being bent horizontally outward at a relatively sharp angle and then horizontally inward in spaced relation to the horizontal outward wall to provide an end closure support shoulder and receiving channel. The top and bottom end members then are firmly secured within such a receiving channel by a thermoplastic cement or other suitable adhesive which produces a strong liquid-proof joint.

Under severe mishandling, leaks have occurred in the bottom end joint of larger size containers made in accordance with the Hothersall design. These leaks have been attributed to the bottom end being partly separated at the base of the truss portion where the bottom end meets the obliquely inwardly bent portion of the body and the outer horizontal support.

The weight of the relatively large quantity of liquid within such a container has a tendency to bow the bottom end outwardly if the filled container is placed upon a concave surface or if it is being carried about by grasping the body without regard to the unsupported bottom. The load or weight of such a liquid tends to pull the joint apart, breaks the paraffin coating at the joint, and sometimes is sufficient to split the fibres of the bottom end or the angular bent portion of the body wall. Such splits or breaks thereafter permit the liquid to leak past or around the joint regardless of the tenacious holding power of the adhesive.

The instant invention contemplates overcoming this difficulty by the formation of an angularly bent end joint. Such construction directs

the disrupting forces which are applied to the bottom end by reason of the weight of the liquid, in the direction of the web material and longitudinally of the adhesive joint. In other words, instead of a pulling apart of the joint the forces of rupture are dissipated in the longer direction of the stock, thereby producing a stronger leak-proof joint.

An object of the invention is the provision of a sanitary fibre container for milk and other beverages having the bottom end member secured between angularly bent folds of the body, so that the resultant action of disruptive forces, due to the weight of the liquid within the container, are directed along the extended linear surface of the material and through a greater holding area of the adhesive in the joint which secure such surfaces together.

Numerous other objects and advantages of the invention will be apparent as it is better understood from the following description, which, taken in connection with the accompanying drawing, discloses a preferred embodiment thereof.

Referring to the drawing:

Figure 1 is a perspective view of a sealed container embodying the present invention; and Fig. 2 is a fragmentary enlarged sectional view taken substantially along a vertical plane suggested by the trace lines 2—2 in Fig. 1.

The container illustrated in the drawing is a preferred embodiment of the invention and briefly comprises a substantially rectangular body 11 closed at its ends with suitable top and bottom closure members 12, 13. The body 11 preferably is formed from a single sheet of fibrous material which is folded at right angles to provide four side walls, designated by the numeral 14. The edges of the sheet are joined along one of the side walls in an overlapped vertically disposed side seam 15 (Fig. 1). These seam edges are secured together with a suitable adhesive and a liquid-tight side seam results. Top and bottom end members 12 and 13 usually are square and are formed of fibrous material. Figure 1 of the drawing shows the top closure member 12 interlocked with adjacent ends or marginal portions of the body in a suitable liquid-proof end joint 16.

For the purpose of forming more rigid end seam joints, particularly at the bottom, the body marginal portions are bent obliquely inwardly as at 17 to form a truss-like structure. The lower edge of the body is then bent outwardly and upwardly as at 18 thereby providing an angular ledge or shoulder 19 which extends circumferen-

tially of the body and upon which the bottom end closure member 13 is supported. The extreme edges of the body marginal portions are then bent inwardly and downwardly over the outer edges of the bottom closure member thus providing opposite end flanges 22 which hold the closure member in position.

The bent parts 18 and 22 of the body adjacent its end and the enclosed margins of the bottom closure member 13 preferably are secured with a suitable liquid-proof adhesive. The liquid-tight end seam joint thus provided is indicated by the numeral 23. Such an angular bent joint tends to bring a marginal corner 24 on the bent part 22, into or nearer the plane of the flat bottom end 13.

An examination of the drawing will show that this construction of body and end members produces a strong end seam joint which directs any disruptive lines of force counter to a pulling apart of the wall sections thus making the joint more resistant to destruction than is the usual form. Should the end member 13 due to the weight of the liquid within the sealed container be bowed downwardly, such weight would tend to direct the line of bow into the long dimension of the angular bend.

The crevices at the joint, designated by the numeral 25, which ordinarily would present a major weakness will not concentrate the disruptive forces in a pull-apart action. In other words, the resultant pressure acting upon this type of end will be directed along the web material and to produce a leak in the joint will have to pull the marginal bottom edges of the end member 13 loose from within the receiving channel formed by the folded body portions 18 and 22 and along the major holding surfaces of the adhesive.

The top end member 12 (Fig. 1) may be reinforced in the same way as the bottom just described. However, ordinarily this is not necessary. Such a top has a hinged closure 26 attached thereto which is adjacent one corner of the container. Such a closure may be the same

as that disclosed in the Hothersall patent herefore referred to. Closure 26 is hinged back for the purposes of filling and dispensing the liquid contents into and from the container. The container body 11 (Fig. 2) when provided for holding a liquid is coated on all of its surfaces by a suitable liquid-proof coating 27 such as paraffin or the like. This makes the fibre container parts liquid-proof.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

20 A rectangular fibre container for liquids comprising a tubular fibre body and a substantially flat bottom end member adhesively secured to folded end portions of said body, said body having a portion adjacent the bottom end thereof bent obliquely inwardly to form a rigid supporting truss portion and thence outwardly at an acute angle to said body portion to form a rigid angular support ledge for the marginal edges of said bottom end member, terminal edges of said body being bent outwardly and thence inwardly over the marginal edges of said flat end member in a leak-proof end seam joint, said joint being disposed closely adjacent and at an acute angle to said obliquely bent truss portion and angularly disposed relative to the horizontal plane of said bottom end member so as to resist tearing apart of the joint under the action of bowing of said flat end member and to direct the disruptive lines of force lengthwise of the joint and into said truss portion, thereby preventing separation of the joint parts and producing a stronger junction of body and end member.
